UNITED STATES PATENT OFFICE.

FRANK C. NEWELL, OF CLEVELAND, OHIO, ASSIGNOR TO THE F. C. NEWELL MUTOGRAPH CORPORATION, OF CLEVELAND, OHIO, A CORPORATION OF OHIO.

STIPPLE MEMBER.

No. 909,444.

Specification of Letters Patent.

Patented Jan. 12, 1909.

Application filed November 16, 1907. Serial No. 402,476.

To all whom it may concern:

Be it known that I, FRANK C. NEWELL, a citizen of the United States, residing at Cleveland, in the county of Cuyahoga, in the State of Ohio, have invented certain new and useful Improvements in Stipple Members, of which the following is a specification.

The invention relates to stipple members for use primarily in display apparatus of the type shown in copending application Serial No. 313,513, wherein it is desired to exhibit on the face of a member the raised characters impressed against the back of the member. The invention has for its principal objects; 15 the provision of an improved and simplified member of the character above indicated, wherein the stipple may be easily assembled in the body of the member and securely held in position; and the provision of an improved 20 construction wherein accidental withdrawal of stipple from advanced position is avoided. One embodiment of the invention is shown in the accompanying drawings, wherein:

Figure 1 is a face view of the stipple members with a portion of the stipple in advanced position to form the letter F.

Figure 2 is an enlarged transverse section through that portion of the plate in which the stipple are advanced, and

Figure 3 is an enlarged detail section through a portion of the member in which the stipple are retracted.

Referring to the drawing, 1 is the stipple member, or plate of dark rubber composition 35 provided with a great number of transverse holes 2, and 3 are the stipple which fit into the holes 2. As shown most clearly in Figures 2 and 3, the stipple consists of three parts, namely the head 4, the shank 5 and the knob 6, and the rear portion of the head is tapered back to the shank or stem in the manner indicated. The rear portions 7 of the openings 2 are reduced in size to prevent the passage of the knobs 6 when the device 45 is in ordinary use, but because of the yielding nature of the material of which the plate 1 is composed, such knobs 6 may be forced through the openings 7, and the difficulty of doing this is reduced if the member 1 is slightly heated. This arrangement permits of the 50 making of the member 1 integral and also the pins or stipple 3, thus reducing the number of parts in the device to a minimum. The stipple are preferably made of aluminum both because of its lightness and be-

cause of its color which contrasts with that of the dark composition plate. The front ends of the stipple are preferably enameled white in order to give a more decided contrast, but because of the color of the metal 60 of the pins this enameling does not have to be done with the same care as would be the case if the pins were of some other color, and any wearing through of the enamel is not readily apparent. The provision of the tapering portions between the heads 4 and stems 2 permits the heads to drop to the position shown in Figure 2, and still be easily pushed back when desired. This feature of construction is advantageous in that, it obviates any accidental jarring of the stipple into rearward position during the operation 65 of the machine. The light weight of the stipple employed, and the slightly yielding character of the material in which they work permits of a practically noiseless operation of the stipple.

Having thus described my invention and illustrated its use, what I claim as new and desire to secure by Letters Patent is the following:

1. A stipple member comprising a body portion provided with a plurality of closely spaced transverse holes, and a plurality of stipple therefor each provided with a head 80 having a conical reduction at the rear portion and a reduced stem portion.

2. A stipple member comprising a body portion provided with a plurality of closely spaced transverse holes, and a plurality of stipple therefor each provided with a head, a reduced stem and a tapering intermediate portion.

3. A stipple member comprising a body portion provided with a plurality of closely spaced transverse holes, and a plurality of stipple therefor each having a reduced shank with a knob at the end thereof, the rear portion of the holes through the member being sufficiently small to normally prevent the 95 passage of the knobs, and the material of the member being somewhat yielding whereby the knobs may be forced through the holes.

4. A stipple member comprising a body portion provided with a plurality of closely spaced transverse holes, and a plurality of stipple therefor each having a reduced shank with a knob at the end thereof, the rear portion of the holes through the member being sufficiently small to normally prevent the 100

passage of the knobs, and the material of the member being adapted to be softened by the application of heat whereby the knobs may be forced through the holes.

- 5 5. A stipple member comprising a body portion provided with a plurality of closely spaced transverse holes, and a plurality of stipples therefor each having a reduced shank with a knob at the end thereof, the rear portion of the holes through the member being sufficiently small to normally prevent the passage of the knobs, and the material of the member being a rubber composition to permit the passage of the knobs through the holes 15 and provide a noiseless support for the stipples.
6. A stipple plate comprising an integral plate provided with a plurality of closely spaced transverse holes with reduced rear portions, and integral stipples therefor each consisting of a head, a knob slightly greater in diameter than the diameter of the reduced portion of the holes and a stem between the head and knob.
- 25 7. A stipple plate comprising an integral

plate of dark rubber composition provided with a plurality of closely spaced transverse holes with reduced rear portions, and integral stipples of white metal therefor each consisting of a head, a knob slightly greater 30 in diameter than the diameter of the rear portion of the holes and a stem between the head and knob.

8. A stipple plate comprising an integral plate of dark rubber composition provided 35 with a plurality of closely spaced transverse holes with reduced rear portions, and integral aluminum stipples therefor each consisting of a head, a knob slightly greater in diameter than the diameter of the rear portion 40 of the holes and a stem between the head and knob.

In testimony whereof I have hereunto signed my name in the presence of the two subscribed witnesses.

F. C. NEWELL.
